UNITED STATES PATENT OFFICE.

JOHN R. WELCH, OF TOLEDO, OHIO, ASSIGNOR TO THE KINSEY MANUFACTURING COMPANY, OF TOLEDO, OHIO, A CORPORATION OF OHIO.

HINGE.

1,091,609.

specification of Letters Patent. Patented Mar. 31, 1914.

Application filed June 23, 1913. Serial No. 775,366.

To all whom it may concern:

Be it known that I, JOHN R. WELCH, a citizen of the United States, and a resident of Toledo, in the county of Lucas and State of Ohio, have invented a certain new and useful Hinge; and I do hereby declare the following to be a full, clear, and exact description of the invention, such as will enable others skilled in the art to which it applies to make and use the same, reference being had to the accompanying drawings, and to the characters of reference marked thereon, which form a part of this specification.

15 This invention relates to hinges and particularly to automobile door hinges of the concealed type, but is not restricted to such use as it may be used in any connection for which it may be adapted or appropriate.

20 The primary object of my invention is the provision of a simple and inexpensive form of hinge of this character, which is capable of having its members easily and quickly engaged one to the other or disengaged without the necessity of inserting or removing screws, which is the present practice, so far as I am aware, thus materially expediting the hanging of automobile doors and minimizing the work incident thereto.

25 30 Further objects and advantages of the invention will be apparent from the following detailed description thereof.

The invention is fully described in the following specification, and while, in its broader aspect, it is capable of embodiment in numerous forms, a preferred embodiment thereof is illustrated in the accompanying drawings, in which,

35 40 Figure 1 is an inner side view of a door casing and door of an automobile body equipped with my invention, with parts broken away. Fig. 2 is an elevation of a hinge embodying the invention with its members in full open position. Fig. 3 is a perspective view of the male member of the hinge, and Fig. 4 is an enlarged perspective view of a portion of the female member of the hinge.

45 50 Referring to the drawings, 1 designates a door frame or casing of an automobile body, and 2 a door mounted therein. The female member of the hinge comprises, in the present instance, a plate or bar 3, which is intended to be secured to one side wall of the door casing by screws, or in any other suit-

able manner, and is provided, in the present instance, with a pair of vertically-spaced socket portions 4, which fit into recesses 5 provided therefor in the wall of the door casing. Each socket 4 may be open at its inner side, 60 but is provided at its outer side at or adjacent to its outer edge with a cross-bar 6, which serves as a stop for limiting the opening movements of the door, as hereinafter more fully described. The bottom wall of 65 each socket 4 is provided with a pivot bearing or hole 7 and the top wall thereof is provided with a slot or recess 8 for the purpose hereinafter described.

70 The male member of the hinge preferably comprises a plate or bar 9 adapted to be secured to a side edge of the door 2 by screws, or in any other suitable manner, and is provided with hinge arms or projections 10 in position to be projected into the respective sockets 4 of the female member. The projections 10 are of L-form that is they project outwardly from one face or side of the plate 9 adjacent to the inner edge thereof, if the door is to swing outwardly 80 relative to the door casing, and having their outer end portions bent or extended across the plate 9 in spaced relation thereto. The outer or free end of each projection 10 is provided at its lower side with a pivot-stud 85 11 for fitting into the bearing hole or opening 7 in the bottom wall of the respective socket 4.

When a hinge arm 10 is mounted in a socket 4 with its stud 11 projected into the bearing opening 7 of the socket, the upper edge of the arm coacts with the top wall of the socket to prevent a raising of the arm relative to the socket for the purpose of removing the stud 11 from its bearing opening, except when the hinge members are in the full open position shown in Fig. 2, in which position the upper edge of the portion of the arm 10 which then projects within the socket is in register with the slot 8 in the top wall of the socket, thus permitting the arm 10 to be raised a sufficient distance to release the stud 11 from its bearing. The free end portion of each arm 10 from which the pivot 11 projects is shown as being enlarged or headed, as at 12, and the upper portion of this enlargement is shortened relative to the depth of the major portion of the arm to permit it to be raised within the socket 4 a sufficient distance to with- 100 105 110

draw its stud 11 from the registering bearing opening 7.

It is evident from the above and from the drawings that the portion of each arm 10 which projects outward from the hinge plate 9 at substantially right angles thereto swings around the associated stop-bar 6 of the female member upon an opening movement of the door 2, and that the laterally projecting free end portion of each arm 10 acts with the bar 6 to limit an outward swinging of the door 2 when it has been opened a predetermined extent. To facilitate an adjustment of the limit of opening movements of a door, an adjusting screw 13 may be threaded through the laterally angled portion of each hinge arm 10 in position to coact with the stop-bar 6 of the female member.

20 It is evident that the hinge plates 3 and 9 having once been secured in proper position to their respective carrying parts need not be removed therefrom to permit a dressing or proper hanging of the door, but that the hinge parts may be easily and quickly engaged or removed as many times as is necessary by simply opening the door a sufficient extent to place the laterally angled portions

of the hinge arms 10 in register with the slots or openings 8 in the top walls of the 30 sockets 4 and then raising the door to withdraw the hinge studs 11 from their respective bearings.

I wish it understood that my invention is not limited to any specific construction or 35 arrangement of the parts except in so far as such limitations are specified in the claim.

Having thus described my invention, what I claim as new, and desire to secure by Letters Patent, is,—

40 A hinge of the class described comprising a socketed member and an angled projecting member for fitting into and pivotally engaging a wall of said socket, and adjustable means carried by one of said members for coacting with the other to limit the relative pivotal movements thereof in one direction.

45 In testimony whereof, I have hereunto signed my name to this specification in the 50 presence of two subscribing witnesses.

JOHN R. WELCH.
